UNITED STATES PATENT OFFICE.

WILLIAM HESS, OF MONROEVILLE, OHIO.

METAL-SEAMER.

SPECIFICATION forming part of Letters Patent No. 395,139, dated December 25, 1888.

Application filed April 25, 1888. Serial No. 271,815. (No model.)

To all whom it may concern:

Be it known that I, WILLIAM HESS, a citizen of the United States, and a resident of Monroeville, county of Huron, and State of Ohio, have 5 invented certain new and useful Improvements in Metal-Seamers, of which the following is a specification, the principle of the invention being herein explained and the best mode in which I have contemplated applying that 10 principle so as to distinguish it from other inventions.

My invention relates to seamers for pressing and flattening the seams of tin and other roofing material.

15 It consists of the improvements hereinafter described and claimed.

Referring to the drawings, Figure 1 is a plan view of the seamer. Fig. 2 is a perspective view of the same. Fig. 3 is a detail view 20 of the wheels and connecting parts. Fig. 4 is a detail view of one of the supports, showing the ratchet and pawl secured thereon. Fig. 5 is an axial section of the seaming device, including pressing and guiding rollers, shaft, 25 and handles.

A is the bed of the seamer, provided at its rear end on either side, respectively, with the half-circular supports a. In the upper portion of each support is the journal-bearing 30 opening a', in which rests the journal b, with which the roll B is furnished at its respective ends. Secured to one of said journals is the crank C, said journal also having secured to it the ratchet c, engaging with the pawl c', attached to support a. Hook c² is pivoted to the central portion of the outer face of one of the supports a, its upper end hooking over the crank-handle and preventing the displacement of the latter. At the forward portion 40 of the bed and on each side of the same I secure the upright stanchions D, provided at their upper portion with the cross-bar d. Said stanchions are further provided on their adjacent faces with the vertical grooves d'.

45 Guide-beams E extend transversely of the bed A and have secured to their opposite extremities the cross-heads e, that fit into the vertical grooves d' and have sliding bearing therein, said guide-beams being some- 50 what separated from each other. Followers f are provided, having at their end portions

tenons f', which fit and have sliding bearing in the said grooves d'. On the upper face of each follower a plate, f², is secured, having bearing against which is the thumb-screw g, 55 that is threaded through each cross-bar d. Intermediate of each follower and its adjacent cross-head I locate the rubber spring g'. On the lower edge of each guide-beam I secure guide-rail h, on which the grooved wheels h' 60 have rolling bearing, said wheels being journaled on shaft J on either side of seamer-wheel K, that rests in the bed of the seamer and travels on the metallic plate k' and in the space between the guide-beams. At either 65 extremity of said shaft are the handles j, though it is to be understood that I may attach upright handles thereto or handles projecting in any desired direction. Between the guide-beams and the roller, and parallel 70 with each, is the compression-roller l, located close to the bed A and journaled on shaft l', which is held in position by springs l², fastened to said bed. Compression-wheel K and guide-wheels h' are journaled on shaft J, 75 while the handles j are rigid with said shaft. The grooved wheels h' have roller guide-bearing on guide-rails h, and serve to guide the compression-roller over the metal to be seamed, preventing any tendency to wobble 80 or bind. Guide-bar m extends along one of the longitudinal sides of the bed and has an opening directly under the guide-beams, through which the seamer-wheel may pass. At a distance away from the guide-bars about 85 equal to the length of a sheet of tin I secure spring-pressed lug m', working in slot m² of ordinary construction, by which the tin is held in position while the seamer operates.

The operation is as follows: The sheets of 90 roofing material are first properly folded and hooked together, and are then slid onto the bed A between the guide-bar and the spring-pressed lug, thereby being firmly held in position. The operator then regulates the tension he wishes the wheel to bear on the seam of the tin. Grasping the shaft-handles, the operator then runs the wheel along the seam, closely pressing and flattening the same. Thence the tin is passed under the roller l, 95 and thence over the wheel B, on which it is wound by the turning of the crank. The con-

stant pressure of the spring acting on the roll 7 keeps the tin in flattened position and prevents the tin from unwinding from the reel.

It will be noticed that I provide two handles 5 on the seamer-shaft, and thus the operator may the more easily operate the same and a greater pressure may be brought to bear on the seam, which is a material advantage. Again, the seamer is attached merely to a bed, 10 and not to a table or standard. It may therefore be easily and readily transported from place to place and set upon any convenient bench for operation.

The foregoing description and accompanying drawings set forth in detail mechanism in embodiment of my invention. Change may therefore be made therein, provided the principles of construction respectively recited in the following claims are retained and employed.

I therefore particularly point out and distinctly claim as my invention—

1. In a seamer, the combination of guide-beams provided, respectively, with guide-rails, 25 a presser-wheel, grooved guide-wheels on each

side of the presser-wheel, said guide-wheels engaging, respectively, with said guide-rails, and a two-handled shaft on which said wheels have bearing, substantially as set forth.

2. In a seamer, the combination of two sets 30 of stanchions located, respectively, on each side of the head of the seamer, said stanchions provided with vertical grooves on their adjacent edges, guide-beams provided with cross-heads having bearings in said grooves, 35 tension devices engaging with said guide-beams, which latter are provided on their under faces with rails, a shaft having grooved bearing-wheels located thereon, and a seamer-wheel located intermediate of said grooved 40 wheels, which have bearing on said rails, substantially as set forth.

In testimony that I claim the foregoing to be my invention I have hereunto set my hand this 16th day of April, A. D. 1888.

WILLIAM HESS.
